UNITED STATES PATENT OFFICE.

CARL R. WALLER, OF TRENTON, NEW JERSEY, ASSIGNOR TO DE LAVAL STEAM TURBINE COMPANY, OF TRENTON, NEW JERSEY, A CORPORATION OF NEW JERSEY.

GOVERNING MEANS FOR MARINE TURBINES.

1,408,049.

Specification of Letters Patent. Patented Feb. 28, 1922.

Application filed September 4, 1919. Serial No. 321,721.

To all whom it may concern:

Be it known that I, CARL R. WALLER, a citizen of the United States, residing at Trenton, county of Mercer and State of New Jersey, have invented a new and useful Improvement in Governing Means for Marine Turbines, of which the following is a full, clear, and exact description, reference being had to the accompanying drawings, which

10 form a part of this specification.

It has been found when geared steam turbines are used for propelling vessels that it is very important to have a governing arrangement which will control the turbine at 15 a predetermined speed, thus preventing it from reaching a dangerously high speed. This governing arrangement is particularly important when the vessel is operating in a high sea, which may cause the propeller to 20 leave the water, thus suddenly changing the load on the driving turbine.

It is also essential that this governing arrangement shall be installed in such a manner that any steam that is used for driving 25 the propelling turbine must go through the governor-controlled valve. Where compound turbines are used, several auxiliary pipes are provided, in order to make it possible to operate one of the turbines, should 30 the other one for some reason fail. In such cases, it is desirable that any steam used for driving any one of the turbines shall go through this governor valve, and that in case of any increase of speed of either turbine shaft, the valve shall be actuated.

35 In connection with geared turbines, it is of the utmost importance that the oiling system should always be in commission, and it is therefore desirable to have some arrangement that will shut down the turbine in case the oiling system should fail.

40 My invention has for its object to control the governor valve so that it will close either in the event of abnormal speed of the turbine or upon failure of the oil supply. The invention comprises a steam supply valve arranged to be opened by a predetermined pressure of oil, such pressure being reducible below said predetermined amount by 45 means for restricting the flow of oil operable by the governor in case of excess turbine speed. By this arrangement, whether the pressure of oil be reduced by its own failure or by a restricted flow due to excessive speed 50 of the turbine, the supply of steam to the

turbine will be cut off until the abnormal condition is removed.

Fig. 1 is a plan view of a compound turbine, showing the manner of application of my invention. Fig. 2 is an elevation of the

60 same. Fig. 3 is a vertical sectional view of a preferred embodiment of my invention combined with a governor of known type.

No details of the invention, except certain 65 pipe connections, are shown in Figs. 1 and 2, which represent a conventional illustration of a compound turbine. The admission of steam to the high pressure turbine *a* and to the low pressure turbine *b* is controlled by 70 the main governor-controlled valve *v* in the valve casing *c*, the inlet for steam being through the pipe *d*.

Both the high pressure turbine and the low pressure turbine are, of course, normally 75 operated, but if, for any reason, it becomes desirable or necessary to cut out the high pressure machine, the low pressure machine can be run independently by closing the manoeuvering valve *e* and opening the 80 valves *f* and *g*, which admit steam respectively to the ahead and astern portions of the low pressure machine.

It will be observed that, whether one or both turbines are in operation, the admission 85 of steam is regulated by the governor-controlled valve *v*.

Both turbine shafts are equipped with governors *h*, each of which controls an oil admission pilot valve *i* connected, through 90 an oil pipe *j* with a piston controlling the main valve, as hereinafter described.

One of the governors *h* is shown in Fig. 3. The turbine shaft *k* is geared to an upright shaft *m* having a housing *n* within 95 which are centrifugally operable weights *o* held in neutral position by springs *p*. When the governor revolves at sufficient speed to throw out the weights, they, through the levers *r*, lift a sleeve *s* on the 100 shaft *m*. The governor is a somewhat simplified form of a known type of governor, but my invention contemplates the employment of any workable governor.

The main valve casing *c* has the steam 105 inlet *d*, and one or more steam outlets. The number of outlets will of course depend upon the particular arrangement on board the vessel, two being shown in the present disclosure.

The valve casing *c* is bolted to a supporting frame *t*. The steam-admission valve *v* is mounted on a spindle *u*, which extends down through a stuffing box *w* into a cylinder *x* formed by the lower part of the supporting frame *t*. On the lower end of the valve spindle *u* is a piston 13 within the cylinder *x*. Threaded on the valve spindle *u* is an adjusting nut *y* between which and 5 a fixed part of the frame *t*, and coiled about the spindle, is a spring *z*. The valve *v*, unless actuated by sufficient pressure of oil against piston 13, as hereinafter described, is held closed, as shown in Fig. 3, by the 10 tension of spring *z*.

The governor-actuated sleeve *s* has pins 10, which engage the forked end of an intermediately fulcrumed lever 11, whose other end is attached to the stem of the pilot 15 valve *i*, hereinbefore mentioned.

Oil from the main oiling system is admitted to the pilot valve casing at 12. The oil outflows from the pilot valve casing through the pipe *j* and enters the cylinder 20 25 *x* back of or under the piston 13 on the valve spindle *u*. Above the piston 13, the cylinder *x* has an oil outlet 14 to a drain line. An oil by-passage 15, in the wall of the cylinder *x*, connects the space below the 30 piston 13 with the space above it, the rate of flow being controlled by a plug 16.

It is obvious, from what has been described, that the valve *c* cannot be moved to admit steam to the turbine unit unless there 35 is sufficient pressure against the piston 13 to overcome the tension of the spring *z*. Let it be assumed that the normal pressure in the main oiling system is maintained at about ten pounds and that it is desirable 40 to shut off steam from the turbine in case the oil pressure should drop to five points or below. It is clear that to start the turbine the oiling system must first be put into service. Specifically, oil is admitted to the 45 pilot valve *i* and flows therethrough unrestrictedly, passing through pipe *j* into cylinder *x*. It is also necessary to create a pressure on the oiling system of above five pounds before piston 13 lifts and opens 50 valve *c*. In other words, steam cannot be admitted through the valve *c* unless the pressure in the oiling system is above five pounds.

Should the turbine unit be in service and 55 if for any reason the oiling system should fail, the valve *v*, upon the drop of oil pressure to five pounds, would immediately start to close.

In case, during service, the turbine speed 60 exceeds normal, the governor *h* will actuate the pilot valve *i* and restrict the passage through the pilot valve to the cylinder *x*. If the speed is high enough, the piston will 65 close the oil passage to such an extent as to cause a drop in oil pressure to five pounds,

or less, whereupon the valve *v* will close. As soon as the turbine speed is reduced to normal, the pilot valve will be operated to allow free flow of oil and cause the oil pressure to mount above five pounds and thus 70 actuate the piston 13 to open the valve *v*.

Having now fully described my invention, what I claim and desire to protect by Letters Patent is—

1. In a governing means for steam turbines, the combination with a turbine unit, of a governor operable thereby, a steam admission valve, a lubricating oil circulating system for the turbine unit, including a constantly open throttling passage causing a 75 predetermined rate of flow from one part of the system to another, means controlled by the governor to vary the rate of flow to the first mentioned part of said system, thereby varying the pressure of oil at one side of 80 said throttling passage, and a movable element connected with and controlling the opening and closing of the steam valve and controlled in its operation by said variation in pressure of oil at one side of the throttling passage.

2. In a governing means for steam turbines, the combination with a turbine unit, of a governor operable thereby, a steam admission valve, a lubricating oil circulating 95 system for the turbine unit, including a constantly open throttling passage causing a predetermined rate of flow from one part of the system to another, means controlled by the governor to vary the rate of flow to the 100 first mentioned part of said system, thereby varying the pressure of oil at one side of said throttling passage, a cylinder communicating with the part of the system to which the rate of oil flow is varied as specified, and 105 a piston in said cylinder connected with and controlling the operation of the steam valve.

3. In a governing means for steam turbines, the combination with a turbine unit, of a governor operable thereby, a steam admission valve, a lubricating oil circulating system for the turbine unit, including a 110 constantly open throttling passage causing a predetermined rate of flow from one part of the system to another, means controlled by the governor to vary the rate of flow to the first mentioned part of said system, thereby varying the pressure of oil at one side of said throttling passage, a cylinder communicating with the system between the throttling 115 passage and the governor controlled means, and a piston in said cylinder connected to the steam valve for actuating said valve.

4. In a governing means for steam turbines, the combination with a turbine unit, 125 of a governor operable thereby, a steam admission valve, a lubricating oil circulating system for the turbine unit, including a 130 constantly open throttling passage causing a predetermined rate of flow from one part of

the system to another, means controlled by the governor to vary the rate of flow to the first mentioned part of said system, thereby varying the pressure of oil at one side of 5 said throttling passage, a cylinder interposed in said system, a piston in said cylinder, said throttling passage connecting the ends of the cylinder on opposite sides of said piston, whereby the piston is subjected to said variable pressure of the oil, and means connecting the piston and steam valve whereby the 10 opening and closing of the latter is controlled by said piston.

5. The combination of a steam turbine and 15 a pressure lubricating system therefor, a valve for controlling the admission of steam to said turbine, a valve actuating device wholly under the control of the pressure in the lubricating system, means for permitting 20 a constant flow of oil through the lubricating system at a predetermined rate to build up pressure to actuate said valve, a governor actuated by the turbine, and a valve con-

trolled by the governor for varying the feed of oil to the system to vary the pressure. 25

6. In a governing means for steam turbines, the combination with a turbine unit, of a steam admission valve, a lubricating oil circulating system for the turbine unit, including a constantly open passage causing 30 a predetermined rate of flow from one part of the system to another, and a movable element connected with and controlling the opening and closing of the steam valve and controlled in its operation by said variation 35 in pressure of oil at one side of the throttling passage, whereby failure to maintain an adequate flow of oil through the system at the last named side of the throttling passage will cause the steam valve to be moved 40 toward its closed position.

In testimony of which invention, I have hereunto set my hand, at Trenton, N. J., on this 22nd day of August, 1919.

CARL R. WALLER.
